MEANS OR MACHINERY FOR CLEARING OR EXCAVATING DITCHES

Douglas Raymond Bomford, Bevington Hall, near Evesham, England, assignor to Bomford & Evershed Limited, Salford Priors, near Evesham, England

Application November 9, 1942, Serial No. 465,033
In Great Britain November 23, 1941

6 Claims. (Cl. 37—103)

This invention relates to means or machinery for clearing or excavating ditches and consists of improvements in or modifications of the means or machinery to be employed for the said purpose described and claimed in United States Letters Patent No. 2,314,763 granted March 23, 1943, the said means or machinery embodying a traversable standard, draw-bar mechanism associated therewith and mechanism mounted on the standard and co-operating with the draw-bar mechanism to effect a sequence of operations on a scoop or bucket provided in conjunction with the machine for gathering and removing the refuse or material from the ditch whereon the machine is designed to operate, the draw-bar mechanism incorporating a longitudinally reciprocable member adapted for connection with the tractor or motor whereby the machine is traversed and with the bucket operating mechanism mounted on the standard.

The present invention has for its object the provision of improved and simplified means or machinery for carrying into effect the invention described and claimed in said patent.

The invention resides primarily in the herein-after described improved or modified means or mechanism mounted on the traversable frame structure of the machine, and controlled through the medium of the reciprocable member of the draw-bar mechanism, for effecting the lowering, raising and lateral motions of the scoop or bucket and in the co-operating means or mechanism whereby the scoop or bucket is tractively connected with the said draw-bar mechanism, and its turning into the position for discharging refuse or material gathered thereby is controlled.

The invention further resides in certain other improvements in or additions to the machine herein-after described and in the machine as a whole.

The invention will now be more particularly described with reference to the accompanying drawings, wherein:

Figure 1 represents in side elevation means or machinery for the purpose specified and embodying improvements or additions in accordance with the present invention, the parts of the machine which control the motions and operation of the scoop or bucket being shown in the positions which they respectively occupy when the said scoop or bucket is lowered to the position for collecting, on the forward traversing of the machine, a load of earth or rubbish to be removed from the excavation or ditch whereon the machine is performing its operations.

Figure 2 is a plan of the same with some parts omitted or partly broken away.

Figure 3 represents in side elevation the scoop or bucket detached from the machine, with the adjoining parts of the arm or member whereby it is tractively connected with the draw-bar mechanism and the associated means whereby it is retained in the normal position, in which it is shown, relative to the said tractive arm while the gathering or excavating operation is being performed and released at the appropriate time to permit it to turn into the discharging position.

Figure 4 is a plan of the said parts of the machine.

Figures 5 and 6 represent in side elevation fragmentary parts of the machine hereinafter more particularly referred to.

Figures 3 to 6 both inclusive are drawn to a larger scale than Figures 1 and 2, which are somewhat diagrammatic owing to the small scale imposed by the limitation of the size of the sheets.

The same numerals of reference indicate the same parts in the several figures of the drawings.

In the embodiment of the invention represented the reference 8, Figures 1 and 2, denotes the longitudinally extending tubular member of the draw-bar mechanism which member is incorporated in and forms part of the fixed frame structure of the machine, and 9 denotes the catch controlled reciprocable member or component which is disposed therein and through the medium of which the requisite lowering, raising and lateral motions of the bucket are effected, the said reciprocable member being adapted, as in the patent aforesaid, for connection at its forwardly presented end with a tractor or motor whereby the machine is traversed and its rear end having connection through a flexible cable 10 with the mechanism from which the bucket

11 is suspended and which is mounted on a rear fixed part of the frame structure of the machine, the said frame structure embodying the aforesaid longitudinally extending tubular member 8, the horizontal bars 12, 12^a of H or girder formation in cross section and to which bars the rearward part of the tubular member 8 is fixed, and the mast or standard 13 which may conveniently be formed from a single bar of H section, the lower end of the said standard being located and fixed in a rearwardly extending part of the tubular member 8 which is cut-away at its upper face to permit the standard to be introduced therein.

The standard 13 is connected by a bracing rod 13^a to the fixed longitudinal member 8 and by the rods 13^b and 13^c to the horizontal bars 12^a.

and 12 respectively, the upper ends of the rods having connection with lugs on a bracket 13^d provided at the upper end of the standard.

The fixed rear part aforesaid of the frame structure is supported at any desired height above ground level by a skid or runner denoted generally by the reference 14 and which is rockably mounted on the lower end of a vertical stem 14^a of angular section and which is adapted to be clamped to a seating constituted by an L or angle bar 12^d fixed to the end of the horizontal bar 12^a and the ends of two inclined rods 12^b, 12^c the other ends whereof are fixed to the bar 12, the said rods in addition to serving to carry the angle bar also serving as a bracing between the bars 12 and 12^a.

The angle bar 12^d carried by the bar 12 and rods 12^b, 12^c has fixed thereto one-half part 15 of each of a pair of clamps 15, 15^a the other and loose parts 15^a of which are secured to the fixed parts 15 by bolts and nuts, the said clamping members co-operating to grip the stem 14^a of the skid in the position to which it is adjusted for regulating the height at which the rear part of the draw-bar and the parts of the frame structure associated therewith are supported above ground level. The two parts denoted by the references 15^b are bars placed against the sides of the stem 14^a opposite the sides embraced by the fixed angle bar 12^d, to pack the space between the sides against which they are placed and the loose parts 15^a of the clamps to take the bearing of said parts 15^a when the bolts by which they are secured to the fixed parts 15 of the clamps are tightened up.

The mechanism mounted on the standard or rear part of the frame structure of the machine and whereby the requisite lowering, raising and lateral motions of the scoop or bucket 11 are effected through the medium of the reciprocable member 9 of the draw-bar mechanism associated with the standard, embodies a derrick or jib 16 which has a universal joint connection with the lower part or base structure of the machine, the said universal joint which is indicated at 16^a being disposed in alignment with the longitudinal axis of the reciprocable member 9 of the draw-bar, and conveniently having its swivelling bearings provided in or on a block secured to an extension of the rear end of the fixed longitudinal member 8 of the draw-bar.

The said derrick or jib 16 which is preferably built up from lengths of tubing as shown is connected to the adjacent end of the reciprocable member 9 of the draw-bar mechanism through the medium of the aforesaid flexible cable 10 or a chain, one end of which is attached to the rear end of the said reciprocable member 9 its other end being connected in any suitable manner to the derrick 16 at a convenient point intermediate the pivoted and free ends thereof, the said cable 10 passing to its connection with the derrick below a guide pulley 17 suitably mounted on the frame structure adjacent the lower part of the standard, as for example on a spindle 17^a supported in bearings provided on the fixed longitudinal member 8, and passing thence upwardly and over a guide pulley 18 having a swivelling or castor-like connection with a socket on the standard at or adjacent the upper end thereof.

It will be appreciated that when the reciprocable member 9 of the draw-bar moves in a rearward direction in the operating of the machine the slackening of the flexible cable 10 allows the derrick 16 to turn downwardly while motion of

the said reciprocable member in the forward direction effects the upward turning of the said derrick.

The scoop or bucket 11 is connected to the free end of the derrick 16 by a flexible cable or chain 11^a, the bucket being furnished for this purpose at or adjacent its rear end with a yoke-like member 11^b to the middle part whereof the cable or chain is attached, the ends of the respective arms or branches of the yoke 11^b having a trunnion or pivotal connection with the respective sides of the bucket so that the bucket can swing freely in the yoke.

The bucket 11 also has a pivotal connection at or adjacent its front upper corners with an arm 19 whereby it is tractively connected to a laterally extending bar or rod 20 at the front end of the base structure of the machine and constituting a part of a triangulated frame structure built from tubing and which supports parts hereinafter more particularly referred to, the said rod 20 and the rod 20^a of this structure preferably having a pivotal connection with the fixed longitudinal member 8 of the draw-bar so as to permit the frame structure to be turned into a more or less vertical position as in the case of the similar parts in the aforesaid patent.

The said tractive arm 19 is conveniently constituted by two parts of rods or tubes interconnected by lattice bracing each pair terminating at the rear end thereof in a member 19^a of triangular formation the said triangular parts being disposed respectively on the opposite sides of the bucket 11 and their rearward ends having pivotal connection with trunnion pins 11^c provided on the bucket. One of the parts 19^a, namely that at the lower side of the plan Figure 4 is omitted from Figure 3.

The pairs of rods constituting the tractive arm 19 converge relative to each other in a forward direction so that their front ends come together and terminate in a socket or on a plate 19^b which has a universal joint connection denoted by the reference 21 with the aforesaid laterally extending rod 20 at the front end of the base structure.

Dogs or catches 22 are provided in association with the bucket 11 for retaining it in the desired position relative to the tractive arm 19 while the bucket is performing its operation on the ditch and until it has been raised and swung laterally to the position at which it is to discharge its contents while the machine is allowed to remain stationary by the appropriate operation of the catch 23 controlling the reciprocable member 9 of the draw-bar as described in said patent.

The dogs 22 may be constituted by shouldered blocks pivotally mounted as at 22^a on the lower sides of the respective triangular parts 19 between which the bucket is pivoted on the tractive arm and interconnected by a transverse rod 22^b to ensure their simultaneous operation, the shouldered parts of the said blocks co-acting with projections 11^d suitably located on the respective sides of the bucket 11.

To provide for an adjustable setting of the said projections 11^d relative to the bucket, for varying the inclination of the bucket on the arm 19 in accordance with the depth of cut to be effected, the projections may be formed on plate-like parts 11^e mounted and adapted for angular motion on the aforesaid trunnion pins 11^c the said plate-like parts being furnished with a plurality of holes 11^f one or other of which can be brought into coincidence with a co-acting hole in the adjoining side of the bucket, a pin

or bolt being passed through the coincident holes for fixing the bucket in the adjusted position relative to the plate-like part.

The automatic release of the dogs or catches 22 at the requisite time in the sequence of operations is effected through the medium of a rod 24 which has operative connection at its rearward end through arms 24^a with the rod 22^b carrying the dogs, the said rod 24 extending longitudinally between the rods forming the tractive arm 19 its forward end being connected to an arm of a double-armed lever 25, under spring control, mounted on the connection of the front end of the tractive arm with the rod 20 of the forward part of the base structure of the machine.

The other arm of the said lever is attached by a flexible cable or chain 26 to a convenient anchorage on the frame structure such as the rod 20^a and this flexible cable or chain remains slack during the raising and lateral swinging of the bucket until the bucket closely approaches the position for discharging its contents when the chain becomes taut thereby arresting the turning motion which the lever 25 performs when the dog operating rod 24 is swung inwardly with the tractive arm 19 and giving a snatch to the rod as the tractive arm completes its inward motion, this operation on the rod 24 effecting the release of the dogs 22 for permitting the requisite tilting of the bucket 11 about its pivotal connections with the tractive arm and the yoke 11^b by which it is connected with the free end of the derrick 16.

The dog operating rod 24 is supported adjacent the arms 24^a whereby it is connected to the rod 22^b by passing it through a hole or bearing in an upwardly projecting arm or bracket 24^b carried by a cross bar 24^c mounted on the lower tubular members of the tractive arm 19, a spring 24^d, in compression, being disposed on the said rod between the bracket 24^b and a boss at the junction of the rod 24 with the arms 24^a, the said spring serving to maintain the dogs 22 in engagement with the projections 11^d on the respective sides of the bucket 11.

For the purpose of regulating the depth of the cut to be performed by the bucket the tractive arm 19 has, or may have, thereon a bent or curved bar 21, omitted from the plan views Figures 2 and 4, which bar depends below the arm in the middle plane thereof, its forward end having a pivotal connection 27^a with the arm and its rearward end which is adjacent the bucket 11 having an upwardly projecting branch 27^b which is furnished with a plurality of holes through one or other of which a pin or bolt can be passed for effecting its connection with a depending lug on a cross-wise disposed rod 27^c on the tractive arm. The bar 27 also serves to ride the tractive arm 19 and bucket from the ditch when the bucket has performed its gathering or cutting operation.

A cowl or shutter 28 is preferably provided at the front end of the bucket 11 for closing the said front end while the bucket is being raised and swung into the discharging position, the said cowl being so shaped and pivotally mounted on the bucket, as for example by the connection of side arms 28^a provided thereon with the aforesaid trunnions 11^c on the bucket, as automatically to turn upwardly into an open position when the bucket is performing a cutting or gathering operation and to resume a closing position while the bucket is being lifted prior to discharging its contents.

The front of the cowl 28 or a web 28^b provided thereon is connected by a chain 29 to a convenient part of or on the tractive arm 19, a hook 24^e provided on the aforesaid cross bar 24^c affording a suitable connection, and when the bucket on its arrival at the position for discharging its contents and on the disengagement of the dogs 22 from the projections 11^d thereon, turns into the discharging position, the chain 29 operates to check the cowl from following the downward tilt of the bucket and consequently the front end of the bucket is opened to allow the contents to fall therefrom.

The web 28^b, where such is provided, as is preferable, is furnished with lateral webs or flanges 28^c on its inclined front edge to give a flat acting face to the said web.

A seat 30 for the person operating the machine, who sits backwards to the direction of motion, is provided at the forward part of the machine, and may be supported on a rod or standard 30^a fixed on the laterally extending member 20 of the triangulated frame structure, the said standard being furnished at its upper end with a box-like or tubular part 30^b with which a bent metal bar 30^c carrying the seat 30 and a back rest 30^d has a spring loaded or dashpot-like connection.

The forward part of the base structure is supported at the desired height above ground level by a skid or runner 31 preferably rockably mounted on the lower end of a stem or rod 31^a which may be adapted for a slidable adjustment in a vertically disposed tube or socket 32 the upper and lower ends whereof are attached to the supporting bar metal members 32^a which are fixed to convenient parts of the base structure.

Means for actuating the catch 23 which controls the sliding motions of the reciprocable member 9 of the draw-bar and also means for effecting a steering control of the lateral thrust resisting flanged wheel 33 which is provided at or adjacent the rear corner of the base of the machine on the side thereof remote from the ditch are provided on the machine in positions adjacent the seat 30 and convenient for operation by the attendant.

The means provided for actuating the said catch 23 may be adapted for hand operation, but preferably as is illustrated in the drawings pedal operated means are employed, the said means embodying the pedal 34 (see Figure 2) carried by a lever 34^a fulcrumed on a spindle 34^b supported in bearings in depending lugs provided on a rod 20^b incorporated in the frame structure and on a parallel bar member 35 the respective ends of which are attached to the said rod 20^b and to a bracing rod or strut 20^c of the frame structure, the said lever 34^a being under the control of a spring 36 anchored thereto and to a convenient part of the base such as the aforesaid strut 20^c, the spring acting to maintain the pedal in its normal position and return it thereto after its operation.

The pedal 34 has connection through a universal joint 34^e with one end of a rod 37 (see Fig. 2) formed of a plurality of tubular sections adapted to telescope relative to each other, but of such cross sectional figure, as for example square, that they turn as one, the other end of the said rod 37 being likewise jointed as at 37^a to an arm 23^a pivoted on the fixed longitudinal member 8 of the draw-bar mechanism, and on downward pressure on the pedal the telescoping sections of the arm 37 extend sufficiently to permit this motion 75 at the same time serving to transmit an upward

turning motion to the arm 23^a. The arm 23^a, as will be best understood by an examination of the fragmentary view shown in side elevation in Figure 5, has connection through the medium of slotted links 23^b with an arm of a bell-crank lever 23^c, pivotally mounted on the longitudinal member 8, the pivot of this mounting having at its end opposite to that whereon the bell-crank lever is fixed an arm 23^d between which end the forwardly extending arm of the bell-crank lever the controlling catch 23 is mounted.

The bell-crank lever 23^c is under the control of a spring 38 which tends to maintain the catch 23 in the locking position, from which it can be withdrawn at the appropriate times by a downward pressure of the foot on the pedal 34, and when this pressure is relieved the parts return to the position in which the catch 23 can enter into engagement with one or other of the notches or other co-acting parts provided in the reciprocable member 9 of the draw-bar mechanism as will be well understood, and for the purpose described in the aforesaid patent.

The lateral thrust resisting wheel 33 is mounted on the inclined lower end of a stub axle or spindle 33^a fitting in a vertical socket 33^b welded or otherwise fixed to the member 12 of the base structure and a steering operation of this wheel may be effected by the provision on the upper end of the axle or spindle 33^a of a bar 33^c the respective ends of which are connected to the ends of a chain 39 which passes around a sprocket wheel 40 on a hand wheel operated steering column 41 mounted on the base frame structure in proximity to the attendant's seat 30 a convenient mounting for the said column being afforded by the platform 42 (see Figure 2) provided on the base structure and which serves the further purpose of a foot rest for the attendant.

Only that portion of the chain 39 which passes round and is adjacent the sprocket wheel 40 need be of the construction requisite for operative engagement by the teeth of the said wheel, the remaining and major part of the chain being of ordinary link formation.

Flexible cables or chains 43, 44 are, or may be, provided to cooperate in checking or steadyng the movements and obviating the lateral overswinging of the derrick or jib 16, the chain 43 being attached at one end to a convenient part on the jib and at its other end to a fixed part of the frame structure as for example to an inclined spar-like member 45 which is fixed at its lower end to the bar 12^a of the base structure, its upper end being braced by wires or rods 45^a and 45^b respectively to the bracket 13^d at the upper end of the standard 13 and to the flange on the lower end of the vertical socket 33^b provided on the frame structure as aforesaid. The chain 44 has connection at one end to the chain 43, intermediate the ends thereof and at its other end to an arm of a check lever 44^a pivoted as at 44^b to the standard 13 the other arm of the said lever being under the action of a spring such as 44^c.

As stated, the chain 43 prevents lateral overswinging of the jib 16, and it will be appreciated that on lateral outward swinging of the tractive arm 19 there is a liability to a sudden snatch on the said chain 43. The chain 44 co-acts with the chain 43 to obviate this liability and does so by sharing the pull or strain imposed on the chain 43, any tendency to snatch being absorbed by the connection of the chain 44 with the check lever 44^a and the damping or cushioning action of the spring 44^c associated with the said lever.

A sprag device may be provided on the machine to arrest its motion in the event of any tendency to over running or skidding which may arise especially when working on clayey or heavy and wet ground, the said device, as is represented in the plan view Figure 2, and in side elevation, slightly modified, in the fragmentary view Figure 6, comprising two pointed spade-like parts 46 disposed at the corners of the front end of a frame-like member 46^a mounted on a spindle 46^b the bearings of which are formed in lugs on the forward ends of ribs 14^b provided on the upper face of the skid or runner 14, the frame-like member being furnished with a rearwardly extending arm 46^c having thereon a counterbalance weight 46^d acting to maintain the sprag in the out of action position, the operation of the sprag for bringing it into its acting position when desired being effected through the medium of a rope or cable 47 one end of which is attached to the end of the arm 46^c, its other end being brought to a suitable location on the machine for permitting its operation by the occupant of the seat 30.

Buffer springs (not shown) may be provided between the connection of the reciprocable member 9 of the draw-bar mechanism with the tractor the said springs being located in a casing 9^a interposed between the said reciprocable member 9 and the member 9^b associated therewith for effecting its connection with the tractor or motor and being designed to operate in both directions of motion of the connected parts.

The various chain or flexible cable connections hereinbefore referred to may where desirable be adapted for an adjustable attachment to the parts with which they are connected.

Means, not shown, and operable through the medium of the tractor, may be incorporated with the machine for facilitating the hoisting of the rods 20 and 20^a and certain parts carried thereby into the vertical position when it is desired to economise space in the storage of the machine, or when it is being traversed from one locality to another.

The manner in which the improved machine described is used and operated for the purposes for which it is designed differs in no material respect from the manner of use and operation of the machine described in the aforesaid patent, and hence no further description is deemed necessary herein.

What I claim is:

1. In a machine for clearing or excavating ditches, the combination of a traversable frame having a member extending laterally thereof, a jib pivotally connected to the frame, means for swinging the jib upwardly and downwardly, a bucket connected to the jib and adapted to occupy a position behind said frame member while the jib is in lowered position, a tractive arm pivotally connected at one end to said laterally extending frame member and pivotally connected at its other end to the bucket for tilting motion of the bucket on a substantially horizontal axis for discharging of material gathered thereby, means for holding the bucket in a position relatively to the tractive arm for clearing or gathering operation, and means controlled by the swing of said jib and tractive arm for releasing said holding means automatically.

2. A machine according to claim 1, wherein said bucket holding means comprises cooperating catch members on the bucket and tractive arm, respectively.

3. A machine according to claim 1, wherein said bucket holding means comprises a catch member on the bucket, and a cooperating catch member on the tractive arm connected to the frame and actuated by swinging movement of the tractive member for disengagement automatically from the catch member on the bucket.

4. A machine according to claim 1, wherein said bucket holding means comprises a catch member mounted adjustably on the bucket for holding the bucket at different angles of tilt on its pivot, and a cooperating catch member pivoted on the tractive arm and having means connecting it to the frame of the machine whereby swinging movement of the tractive arm retracts it automatically from the catch member on the bucket.

5. A machine according to claim 1, wherein the bucket is suspended from the jib by a flexible member, and said tractive arm is connected to

said laterally extending frame member by a universal joint.

6. In a machine for clearing or excavating ditches, the combination of a traversable frame, a jib having a pivotal connection with the frame, a bucket suspended from the jib for removing material from a ditch, cable means connected to the jib for effecting raising and lowering and lateral movements of the bucket, and jib controlling means for steadyng and preventing lateral overswinging of the jib comprising a chain connected at one end to the jib and at its other end to a fixed part of the frame, a second chain connected at one end to the first mentioned chain at a point between its ends and extending transversely thereto, and a spring controlled check lever mounted on the frame and connected to the other end of said second chain.

DOUGLAS RAYMOND BOMFORD.
